UNITED STATES PATENT OFFICE

THOMAS J. DELANY AND JOHN B. MORGAN, OF KANSAS CITY, MISSOURI,
ASSIGNORS TO THEMSELVES AND ADAM C. HURD, OF SAME PLACE.

MAGNETIC WHEAT-CLEANER.

SPECIFICATION forming part of Letters Patent No. 243,862, dated July 5, 1881.

Application filed April 6, 1881. (No model.)

To all whom it may concern:

Be it known that we, THOMAS J. DELANY and JOHN B. MORGAN, of Kansas City, in the county of Jackson and State of Missouri, have 5 invented a new and useful Improvement in Magnetic Wheat-Cleaners, of which the following is a specification.

Figure 1 is a sectional side elevation of the improvement. Fig. 2 is a perspective view of 10 one of the cylinders.

The object of this invention is to furnish cleaners for separating pieces of wire and other iron or steel from wheat or other grain.

Similar letters of reference indicate corresponding parts.

A represents a spout connected with a thrashing-machine, mill, or other machine or place where grain is passed through a spout. In 20 openings in the opposite sides of the spout A are pivoted cylinders in such positions that half, or nearly half, of the said cylinders may project into the said spout. The faces of the cylinders are formed of wide magnetic surfaces B and narrow non-magnetic surfaces C.

To the ends of the cylinders B C are attached gear-wheels D, of a larger diameter than the said cylinders B C, so that the gear-wheels D of adjacent cylinders will mesh into each other, and the adjacent cylinders will 25 revolve in opposite directions. Motion can be given to any one of the series of cylinders from any convenient power. With this construction a zigzag channel is formed through the spout A in such a manner that the grain

30 will be projected against the faces of the revolving cylinders B C alternately, so that any pieces of wire or thrasher-teeth, or other pieces of iron or steel that may be in the grain, will adhere to the magnetic surfaces B and be carried out of the spout A.

To the spout A, opposite or a little above each cylinder B C, are attached two bars, arms, or brackets, E, which project across the ends, or are curved downward around the ends of the outwardly-projecting parts of the cylinders B C, so that their outer ends may be below the centers of the said cylinders. 45

To the ends of the arms E are attached bars or scrapers F, which extend longitudinally across and close to the lower outer parts of 50 the faces of the cylinders B C, as shown in Fig. 1. With this construction any piece of iron or steel that may adhere to the magnetic surfaces B of the cylinders will be pushed along the said magnetic surfaces B until they 55 come to the non-magnetic surfaces C, when they will drop off and fall down upon the outside of the spout A. By this construction all pieces of iron or steel that may be in the grain will be conveniently and certainly removed. 60

Having thus fully described our invention, we claim as new and desire to secure by Letters Patent—

The combination, with a grain-spout having side openings, of pivoted cylinders projecting 65 into said spout and having magnetic as well as non-magnetic surfaces, the gear-wheels D, arranged on the ends of said cylinders, the brackets E, having their ends below the centers of said cylinders, and the scrapers F, attached to said brackets, as shown and described. 70
